UNITED STATES PATENT OFFICE.

HENRY W. BUHLER, OF BOSTON, MASSACHUSETTS.

COKE-OVEN.

1,319,842.

Specification of Letters Patent. Patented Oct. 28, 1919.

Application filed January 27, 1917. Serial No. 144,961.

To all whom it may concern:

Be it known that I, HENRY W. BUHLER, a citizen of the United States of America, residing at Boston, county of Suffolk, 5 State of Massachusetts, have invented certain new and useful Improvements in Coke-Ovens, of which the following is a specification.

My invention relates to heating apparatus generally, but more specifically comprises the application of the principles of heating involved therein to an improved form of regenerative and reversible coke oven. The object of the invention is to produce a heating action on ovens of this type which shall be flexible of control, even, and uniform during both cycles of operation, and a structure in which all parts shall be accessible for observation and manipulation. 15 The best form of apparatus at present known to me embodying my invention is illustrated in the accompanying drawings in which

Figure 1 is a vertical cross section of a 25 battery of ovens taken on planes passing through the heating flues and their connections parallel to the longest dimensions of the coking retorts or ovens but not passing through any of said ovens. The sections are 30 taken on broken line 1^a—1^a—1^b—1 of Fig. 3, and on line 1—1^a, and broken line 1^b—1 of Fig. 2, parts being broken away.

Fig. 2 is a longitudinal vertical section of the same battery of ovens taken on lines 35 2—2 of Figs. 1, 3 and 4, looking to the left, and parts being broken away.

Fig. 3 is a plan view on broken line 3—3 of Fig. 1, parts being broken away, and

Fig. 4 is a diagram in plan illustrating 40 the circulation of the air and fuel and products of combustion.

Throughout the drawings like reference characters indicate like parts. 1, 1, (Fig. 2) represent four of an indefinite series of 45 coking chambers, retorts or ovens which have their greatest dimensions horizontal and perpendicular to the plane of Fig. 2. In other words they are long, narrow, but comparatively high chambers stretching 50 from one face to the other of the upper portion of the structure shown in Fig. 1. They are separated one from another by pairs of intervening walls 2, 2. (See Fig. 2). The members of each pair of walls 2, 2, are 55 joined together by bonding walls 5, 5^a. (Fig. 1). As a result there are formed a series

of vertical flues 3, 4, arranged in tandem between the retorts 1, 1, etc. While the bonding walls 5^a, 5^a, (that is to say every other bonding wall in each series) are built 60 solid all the way to the roof or top wall 35, the alternate bonding walls 5, 5, have their upper extremities reduced in thickness, as shown at 6 (see Fig. 1) and pierced by a port 7, the effective area of which may be 65 varied by lateral sliding of damper 8, on ledge 9. Thus each flue 3, is connected to its right hand neighbor 4 (looking at Fig. 1) by port 7, so as to form a couple or pair. This is rendered a reversible heating pair 70 by having a fuel connection at the bottom of each flue and also a second connection which may serve either as an air or waste gas connection, and then having means for manipulating these connections so that 75 when air and fuel are admitted to the bottom of one member, as 3, of each pair of flues, the fuel connection to the other flue 4, of the pair is closed and the other passage-way thereto serves as a waste gas conduit, 80 and vice versa, when the fuel and chimney connections are reversed.

The fuel supply pipes are placed in galleries 22, below the ovens. As shown there is one gallery for every two retorts and consequently for every two rows of heating flues, but this arrangement might be varied. In each gallery are two fuel pipes which are placed at different levels so their branches may extend in horizontal lines without interfering one with another. 26^a is the upper one and 26 the lower one. Pipe 26, has a series of branches 27, extending to right and left and then upward to form burners 28, in passages 33, leading to the heating 90 flues. Pipe 26^a, has similar branches 27^a, connected to burners 28^a. The left hand branches 27, and burners 28, of the lower pipe 26, extend to the vertical flues 3, of the left hand row of flues (looking at Fig. 2) 100 while its right hand branches 27, and burners 28, extend to the flues 4, of the right hand row of flues, the right and left hand branches being staggered as shown in diagram in Fig. 4. In Fig. 2, flues 3, are behind flues 4, and do not show in that figure, but their connections 30 and 31, from conduits 17, 17, and 30^a, and 31^a, from conduits 17^a, 17^a, show in dotted lines. Conversely 105 the left hand branches 27^a, and burners 28^a, of upper pipe 26^a, connect with the flues 4, of the left hand row of flues and the right

hand branches and burners connect with the flues 3, of the right hand row of flues (looking at Fig. 2), all as shown clearly in diagram in Fig. 4. The two sets of burners 5 28^a, and branches 27^a, of pipe 26^a, are staggered oppositely to those 28, and 27, of pipe 26. The flow of gas from each burner may be adjusted by cocks 37, 37, (see Fig. 2).

When one gas pipe 26, is connected to a 10 source of fuel supply by opening valve 36, so that its burners are thrown into operation, the other pipe 26^a, is shut off by closing its valve 36^a, so that its burners are out of operation. Assuming that gas is flowing 15 from pipe 26, in any gallery 22, it passes to the left up through burners 28, to the bottoms of flues 3, of the left hand row, and hot air also enters these flues from air conduit 17, through branches 30, and vertical passages 31, shown in dotted lines in Fig. 2. As the gas and hot air combine they pass up flues 3, of the left hand row, as indicated by dotted arrows in Fig. 2, through ports 7, and down the flue 4, of 20 each pair of that row, as indicated by full line arrows in Fig. 2, thence by passages 31^a, and branches 30^a, indicated in full lines in Fig. 2, to left hand conduit 17^a, which is connected to the chimney flue during this 25 cycle. In the same way gas passes to the right through burners 28, to the bottoms of flues 4, of the right hand row, mingles with air from conduit 17, delivered through branches 30 and 31, burns in flue 4, passes 30 up through port 7, as shown by full line arrows, down flue 3, of each pair as shown by dotted arrows, to right hand conduit 17^a, and to the chimney. As pipe 26^a, is shut off, all the burners 28^a, connected to it are 35 dead and exercise no function during this cycle. The burnt gases pass out of left hand flues 4, and right hand flues 3, to the conduits 17^a, the burner pockets 33, at the bottom of these flues being merely dead ends 40 for such flues.

During the opposite cycle of operations pipe 26, is shut off and gas is turned on to pipe 26^a. Conduits 17^a, are supplied with hot air, conduits 17, are connected to the 45 chimney flue and all the above described operations are reversed.

10, 10, are passageways through roof 35, in line with flues 3, 3, normally closed by covers 11. Similarly 12, 12, are passages in 50 line with flues 4, 4, normally closed by covers 13, 13.

The conduits 15, 15^a, 17, 17^a, which are used alternately for hot air and gases of combustion, do not extend continuously 55 through the structure, but are separated by walls 14, 14^a, located in planes approximately midway of the lengths of the retorts and at right angles thereto, into two groups. The members of one group are marked 15, 60 15^a, and the numbers of the other group

are 17, 17^a. One group, as 15, 15^a, serves the heating flues grouped about one group of adjacent ends of the retorts, *i. e.* the right hand ends looking at Fig. 1, while the other group 17, 17^a, serve the flues at the other ends of the retorts. Each pair of conduits 15, and 17, are in line one with the other but are separated by wall 14. Similarly, each pair composed of a conduit 15^a and a conduit 17^a, has its members in line but 70 separated by wall 14^a. Each conduit is connected to a regenerator. Those serving conduits 15, 15^a, are marked 16, 16^a, respectively, and those serving conduits 17, 17^a, are marked 18, 18^a, respectively. Each regenerator 16, 16^a, has an air supply connection 21, to the upper part of a gallery 22, controlled by damper 21^a, and a connection to a chimney flue 23, controlled by damper 20^a. Gate 20, closes the air connection 21, 75 when the chimney flue connection is opened, and vice versa. Similarly each regenerator 18, 18^a, has an air supply connection 25, to the top of a gallery 22, controlled by a damper 25^a, and a connection to a chimney flue 24, controlled by a damper 19^a. Similarly, gate 19, closes the air connection 25, when the chimney flue connection is 80 opened, and vice versa.

The lower ends of passageways 33, for 90 the gas burners 28, 28^a, and of the air and waste gas passageways 31, 31^a, normally closed by suitable covers or caps 29. Access to these can be had from galleries 22, in 95 the oven foundations.

The general scheme of operation is clearly shown in diagram in Fig. 4, and indicated by arrows in the other figures of drawing. Each alternate regenerator as 16, 16, at the right hand ends of the retorts, and 18, 18, 100 at the other ends is working on air during the cycle there depicted. The gates 19, are in position to close connections from conduits 17, and regenerators 18, to chimney flue 24, and open air inlets 25, to said regenerators and conduits. The gates 20, on 105 the other hand, shut off regenerators 16, and conduits 15, from chimney flue 23, and open them to air inlets 21. Consequently, the draft of chimney flue 24, is exerted to draw 110 fresh air through regenerators 18, (by which said air is heated) into conduits 17, from whence the air so heated is distributed through passages 30, to the flue couples, passing first to combustion flues 4, of the 115 couples above conduits 17, and to combustion flues 3, of the couples below conduit 17, as shown in diagram Fig. 4. Here the hot fresh air meets the gas entering these flues through mains 26, branches 27, and 120 burners 28. The combustible mixtures so formed begin to burn in these flues and the burning and burnt gases so formed pass through ports 7, down vertical flues 3, of the 125 couples above conduits 17, and vertical flues 130

4, of the couples below conduits 17, as shown in diagram, Fig. 4, out through passages 30^a to conduits 17^a, to and through regenerators 18^a. After heating these regenerators the 5 burnt gases then pass to chimney flue 24. In the same way chimney flue 23, pulls air through regenerators 16, and conduits 15, into the members of the pairs of heating flues 3—4, being supplied with gas from 10 main 26, and out through the other flue of each pair to adjacent conduits 15^a, and regenerators 16^a. When the regenerators 16 and 18, have fallen to the lowest permissible temperature and 16^a and 18^a, have been 15 heated sufficiently by the waste gases, all gates 19, and 20, are reversed in position, gas valves 36, are closed and 36^a opened. Thereupon, gas main 26^a, feeds through 20 branches 27^a and burners 28^a, and the direction of flow through all conduits and flues is reversed.

In the above described operation the effective draft on any one pair of heating flues 3—4 varies with the distance of the outlet 25 of the pair from the chimney flue. Thus, if the effective pull of flue 23, is four ounces, and the friction of regenerator 16^a, and connection up to the extreme right hand flue 4 (looking at Fig. 1) and other causes reduce 30 that to three ounces, the friction in conduit 15^a and other causes may reduce it to one ounce or less at the mouth of the last flue 4, to the left, connected to conduit 15, i. e., the flue 4, nearest division wall 14. If no means 35 for counteracting this difference of draft existed there would be intense combustion in the flues at each end of each retort 1, shading off to very feeble combustion in those at the middle of each retort, and unequal coking 40 action would result. With my invention this tendency can be counteracted by adjusting dampers 8, by tools inserted through openings 10, so that the ports 7, of the first mentioned flue pairs shall have reduced 45 opening and those of the flue pairs last mentioned shall have larger openings. Thus the less powerful draft at the middle zone can pull the air necessary for normal combustion through the flue couples in that zone, 50 while the more powerful draft on the flue couples at the end zones is able to pull only an equal quantity of air through the restricted port openings of the flue couples in those zones. The proper amount of fuel for each 55 flue couple is secured by initial adjustment of burner cocks 37, 37. When these and dampers 8, have been once properly adjusted little further individual manipulation will be required. The proper group combustion 60 is then controlled by manipulating air damper 21^a, and chimney damper 20^a, for one end and dampers 25^a and 19^a, for the other. These group dampers can be adjusted from time to time to compensate for 65 varying atmospheric conditions, etc.

Cleaning and inspection of the flues 3—4 can be effected through openings 10 and 12, from the top or through channels 31, 31^a, and 33 from the gallery 22, below, by removing covers 29, 29.

By taking air from the upper part of galleries 22, 22, below the ovens, a considerable initial heating of the air before it reaches the regenerators is realized and the fuel pipes and cover plates 29, are kept 70 from being overheated. Another advantage of the invention resides in the uniformity of draft on any given couple of flues 3—4 during both cycles of operation. This results from dividing the conduits 15, 15^a, 17, 17^a, into sections, each open only at the outer end, and placing the regenerators at those open ends. Thus, taking the right hand flue couple or pair 3—4, looking at Fig. 1, the draft will be substantially the same whether 80 chimney flue 23, is pulling through conduit 15^a, on flue 3, on one cycle, or through conduit 15, on flue 4, on the other cycle, the distance of the mouth of flue 3 from regenerator 16^a being only a few inches more than 90 the distance of the mouth of the flue 4, from regenerator 16. Thus, even, uniform heating conditions are maintained throughout both cycles of operation. If, however, the walls 14, 14^a, were removed and conduits 95 15—17 15^a—17^a, were continuous, one being served by a regenerator, as 16, at one end, and the other by a regenerator, as 18^a, at the other end, it is clear that when the chimney pull was through the nearer regenerator 16, 100 this flue couple would get a powerful draft, while during the other cycle when the chimney pull was through the much more distant regenerator 18^a, this flue couple would get only a weak draft. Consequently an adjustment of damper 8, which would be right 105 for one cycle would be exactly wrong for the other cycle, and uniform, even coking action during all cycles of operation could not be secured.

With my invention this individual and inter-group uniformity of action can also be maintained while flexibility of mass action is retained. The retorts 1, usually taper in width slightly from one end to the other 115 to facilitate expulsion of the coke by rams operating always from adjacent retort ends. This makes a thicker body of coal at one end of the retort than at the other and calls for slightly larger heating flues, or more active 120 combustion in the groups of flues, at those ends. This requires that one set of regenerators, as 16, 16^a, shall have a larger capacity than the other set 18, 18^a. The principle of segregating the heating flues into 125 groups at each retort end and which are served by separate regenerators lends itself perfectly to the above indicated requirement, as each regenerator can be built to suit the particular groups of flues which it serves, 130

and it is never called upon to serve any others.

I wish it understood that various changes can be made in the details of construction shown and described without departing from the substance of my invention so long as the general principles of operation and coaction of parts herein set forth are preserved.

10 Having described my invention, I claim:

1. In a coking apparatus the combination of a series of retorts, heating flues in the walls between said retorts, which flues are connected together in couples, gas burners located in the ends of all the flues, a series of galleries under the retorts extending parallel thereto, there being one such gallery for every two retorts, and a pair of gas mains in each gallery, equipped with branch pipes extending to the burners, one main being thereby connected to one flue of each of the couples in the wall at the right of the retort immediately above it, and to the other flue of each of the couples in the wall at the left of said retort, while the other main is connected to the remaining flues of all the couples, said mains being equipped with closure means by which a supply of gas for their connected burners may be sent through one main only of each pair at any one time.

2. In a coking apparatus the combination of a plurality of horizontally extending retorts, a series of vertical heating flues formed in each wall between adjacent retorts connected together in pairs by ports at adjacent ends of the flues, a plurality of conduits each of which is connected to all one set of members of the flue pair in the wall adjacent one side of a retort at the flue ends farther removed from the above mentioned ports, and similarly connected to all the other set of members of the flue pairs adjacent the other side of that retort, burners connected to the same ends of all flues, a partition wall located approximately midway of the length of the retort but not cutting it, dividing the conduits into two sections and the flues into two groups, and a regenerator connected to each conduit section.

3. In a coking apparatus the combination of a series of retorts, heating flues in the walls between said retorts, which flues are connected together in couples, gas burners located in the ends of all the flues, a series of galleries under the retorts extending parallel thereto, there being one such gallery for every two retorts, and a pair of gas mains in each gallery, equipped with branch pipes extending to the burners, one main being thereby connected to one flue of each of the couples in the wall at the right of the retort immediately above it, and to the other flue of each of the couples in the wall at the left of said retort, while the other

main is connected to the remaining flues of all the couples, said mains being equipped with closure means by which a supply of gas for their connected burners may be sent through one main only of each pair at any one time, said coking apparatus also being provided with a sole flue below each retort, which sole flue has branch connections to the lower ends of one member of each flue couple on one side of the retort above it, and to the lower end of the other member of each flue couple on the other side of said retort, together with regenerators connected to said sole flues and means for reversing the flow of air and waste gases through said regenerators and flues.

4. In a coking apparatus the combination of a plurality of horizontally extending retorts, a series of vertical heating flues formed in each wall between adjacent retorts connected together in pairs by ports at adjacent ends of the flues, a plurality of conduits each of which is connected to all one set of members of the flue pairs in a given series in the wall adjacent one side of a retort at the flue ends farther removed from the above mentioned ports, and similarly connected to all the other set of members of the flue pairs in a given series adjacent the other side of that retort, burners connected to the same ends of all flues, and a regenerator connected to the outer ends of each one of the conduits.

5. In a coking apparatus the combination of a plurality of horizontally extending retorts, a series of vertical heating flues formed in each wall between adjacent retorts connected together in pairs by ports at adjacent ends of the flues, a plurality of conduits each of which is connected to one set of members of the flue pair in the wall adjacent one side of a retort at the flue ends farther removed from the above-mentioned ports and similarly connected to all the other set of members of the flue pairs adjacent the other side of that retort, burners connected to the same ends of all flues, a partition wall located approximately midway of the length of the retort but not cutting it, dividing the conduits into two sections and the flues into two groups, and a regenerator connected to each conduit section.

6. In a coking apparatus the combination, with a series of horizontally extending retorts, a series of couples of heating flues in the walls between the retorts, conduits below the retorts, each conduit being connected to the ends of one set of members of the flue couples on one side of the retort above it, and to the ends of the other set of members of the flue couples on the other

side of the retort, and gas supply connection to all said flues, of centrally disposed vertical partition walls extending transversely of the conduits dividing said flue couples 5 and conduits into two groups, a separate regenerator connected to the outer end of each conduit, means for reversing the flow of air through said regenerators, conduits and flue couples, and means for controlling the gas 10 connections so that gas shall be supplied only to those members of the flue couples to which air is being supplied.

7. In a coking apparatus the combination of a plurality of retorts, a plurality of sets 15 of flues arranged between adjacent retorts, each set of flues between any two retorts be-

ing connected in pairs, a plurality of conduits corresponding to the retorts, one member of each pair of one set of flues being connected to the conduit on one side of it 20 and the other member of each pair of that set of flues being connected to the conduit on the other side of it, and a separate regenerator connected to each conduit, the regenerators being connected to the conduits at 25 adjacent ends of the conduits and the other ends of the conduits being closed.

HENRY W. BUHLER.
